[57] CLAIM

The ornamental design for traffic bollard, as shown and described.

DESCRIPTION

FIG. 1 is a partial front sectional view of a traffic bollard showing my new design, taken along line 1—1 in FIG. 3 with the rear being a mirror image; FIG. 2 is a side elevational view thereof, with the opposite side being a mirror image; FIG. 3 is a top plan view thereof; FIG. 4 is a bottom plan view thereof; FIG. 5 is a perspective view thereof; FIG. 6 is a front elevational view of a second embodiment thereof with the rear being a mirror image; FIG. 7 is a side elevational view thereof, with the opposite side being a mirror image; FIG. 8 is a top plan view thereof, wherein the bottom is the same as the first embodiment shown in FIG. 4; FIG. 9 is a front elevational view of a third embodiment thereof with the rear being a mirror image; FIG. 10 is a side elevational view thereof, with the opposite being a mirror image; FIG. 11 is a top plan view thereof, wherein the bottom is the same as the first embodiment shown in FIG. 4; FIG. 12 is a front elevational view of a fourth embodiment thereof with the rear being a mirror image; FIG. 13 is a side elevational view thereof, with the opposite side being a mirror image; and, FIG. 14 is a top plan view thereof, wherein the bottom is the same as the first embodiment shown in FIG. 4.
